SOFA BED

Jack B. Craham, Minneapolis, Minn., assignor to
 Flexsteel Spring Corporation, Minneapolis,
 Minn., a corporation of Minnesota

Application March 1, 1950, Serial No. 147,000

8 Claims. (Cl. 5—18)

1

My invention relates to sofa beds and particularly to the seat bottoms thereof and has for an object to provide a front seat bottom and a rear seat bottom with interfitting transversely extending elongated parts adapted to be intermeshed to form a sofa seat bottom or to be pulled apart to form a bed bottom of a width almost equal to the combined width of the front and rear seat bottoms.

Another object of the invention resides in providing the elongated parts with transverse surfaces lying in a substantially horizontal plane.

A still further object of the invention resides in constructing each seat bottom with a base, and with ribs extending transversely thereof and with springs extending between the ribs and bases.

An object of the invention resides in constructing the springs as arcuate leaf springs.

A still further object of the invention resides in arranging certain of the ribs of one bed bottom in alternation with certain of the ribs of the other bed bottom.

An object of the invention resides in constructing the bases with spaced transverse slats and with longitudinal base members at the end of the slats and to which the springs are attached.

Another object of the invention resides in providing casters attached to the slats and supporting the seat bottoms for relative movement in the direction of the ribs.

A still further object of the invention resides in arranging the bases at different elevations to clear one another.

A feature of the invention resides in utilizing a seat cushion and a back rest cushion and in hinged connecting the cushions together with a flap adapted to be assembled to form a bed bottom.

An object of the invention resides in making the flap of a length equal to the thickness of the cushions.

Other objects of the invention reside in the novel combination and arrangement of parts and in the details of construction hereinafter illustrated and/or described.

The herein disclosed invention comprises front and back seat bottoms which are similar in construction. Each seat bottom consists of a base including a number of transverse slats and to the ends of which are attached longitudinal base members. Casters secured to the slats support the bases for transverse relative movement. Disposed above the slats are ribs which are con-

nected to the longitudinal base members by means of arcuate springs. Certain of the ribs overlie the slats. The slats of the base of the rear seat section are disposed below the base of the front seat section so that said bases clear one another during relative movement of the seat bottoms while the longitudinal base members of the rear section are mounted on posts and situated above the slats of the front seat section so that said base members likewise clear one another. The ribs of the two bottoms are disposed in interfitting relation so that the two bottoms may move relative to one another in a direction parallel to the ribs. The two seat bottoms are disposed in a sofa frame constructed in the conventional manner and which is upholstered to give the same the desired utility and appearance. Employed with the seat bottom is a seat cushion and a back rest cushion. These cushions are adapted to be positioned adjacent one another to overlie both of the seat bottoms when the two bottoms are in extended position to form in combination a bed bottom. The two cushions are connected together by means of a flap which is connected to the upper rearward edge of the seat cushion and to the lower forward edge of the back rest cushion. This flap is of a length equal to the thickness of the cushions. When the seat bottoms are collapsed the back rest cushion may be set on edge on the seat cushion a distance forwardly of the rearward edge thereof determined by the length of said flap and supported by a suitable back rest support carried on the frame of the sofa. In this manner the seat cushion may be made of a suitable length to provide comfortable seating.

In the drawings:

Fig. 1 is a plan view with portions broken away of a sofa bed illustrating an embodiment of the invention.

Fig. 2 is a cross sectional view taken substantially on line 2—2 of Fig. 1 and showing the seat cushions in extended position.

Fig. 3 is a view similar to Fig. 2 showing the parts in collapsed position.

The invention consists of a sofa frame 10 which may be of ordinary construction suitable for upholstery. Associated with this frame is a forward seat bottom 11 and a rearward seat bottom 12 which are movable with respect to the frame 10 to form a sofa arranged for comfortable seating or a full width bed. These parts will now be described in detail.

The frame 10 consists of two end frame sections 13 and 14 which are identical in construc-

tion. Only the frame section 14 will be described in detail. This section comprises an arm rest 16. Legs 17 and 19 are secured to the arm rest 16 and to cross bars 18, which are disposed at the lower portion of the section. An end panel 15 is secured to the parts 16, 17, 18 and 19 on the outer side thereof. Secured to the rearward portions of the end sections 13 and 14 is a rear section 21. This section comprises three longitudinal frame members 76, 77 and 78 which are attached to uprights 79. These uprights are secured to the legs 19 by means of bolts 80 whereby the end sections 13 and 14 are secured to the rear section 21. The end sections 13 and 14 are further secured together at their forward ends by means of a tie bar 81 which extends through the cross bars 18 of frame sections 13 and 14 and which is threaded at its ends to receive nuts 82. These nuts engage the cross bar 18 on opposite sides thereof and clamp the parts together.

Forwardly of the frame section 21 and carried by the upper part of the same is a back rest 23. This back rest is spaced from the section 21 and is supported on end pieces 24 secured to the uprights 79. In addition the said back rest is attached to a longitudinal frame member 83 which is also secured to said end pieces. Adjacent the said frame member is another longitudinal frame member 84 attached to the end pieces 24 and to the longitudinal frame member 77 of the rear section 21. Mounted on the longitudinal frame members 83 and 84 is a sheet of plywood 85 or similar material and the longitudinal frame members 76 and 77 of frame section 21 have similarly attached to them another sheet of plywood 86. By means of this construction a compartment 25 is formed in which bedding may be stored. This compartment is closed by means of a cover 26 connected to the upper edge of the longitudinal frame member 76 of rear frame section 21 by means of hinges 27.

The lowermost portions of the frame sections 13 and 14 have attached to the cross bars 18, the legs 17 and the longitudinal frame member 78 of rear section 21, blocks 50 which serve as feet for the sofa. The frame 10 is upholstered in the customary manner which, not forming any feature of the invention, has not been shown in detail, and which has been indicated in dotted lines at 51.

The two seat bottoms 11 and 12 are disposed between the two sections 13 and 14 of frame 10 and may be moved partially outward therefrom or disposed substantially within the confines of said section and below the back rest 22.

The seat bottom 11 comprises a base 28 which consists of a number of slats 29 extending transversely of the sofa and arranged in spaced relation. Overlying the slats are a corresponding number of channel bars 30 which have secured to them three longitudinal base members 31, 32 and 33 which are also channel shaped in form. The base members 31 and 33 are situated near the ends of the said slats while the member 32 is situated near the centers of the same. The base 28 further includes an edging 45 which is secured to the slats 29. Mounted at each corner of the base is a block 46. To these blocks are secured casters 47 which support the base for transverse movement in the direction of extent of the said slats.

Overlying the base 28 are a number of ribs 34 which are constructed of a thin flexible material. These ribs are held in spaced relation by means

of tie bars 148 which are secured to said ribs by means of rivets 149. The ribs 34 are arranged in pairs indicated at 66 and the ribs of each pair have secured to the ends thereof U-shaped leaf springs 35 and 36 which in turn are attached to the base members 31 and 33 by means of rivets 37. These ribs are secured to the upper ends of the springs 35 and 36 by means of other rivets 38. Overlying the forward ends of the said ribs are leaf springs 39 which are secured under the rivets 38. Clips 40 are attached to the forward ends of the said leaf springs and support an edging wire which serves the usual purpose. The rearward ends of the ribs 34 extend rearwardly of the springs 36 and have attached to them similar clips 42 which support a rear edging wire 43. Attached to the ribs 34 of each pair 66 of ribs is an intermediate arcuate leaf spring 48 which is secured to the said ribs and also to the longitudinal base member 32. The springs 48 are secured to the ribs 34 by means of rivets 49 and serve to tie the parts together and form a rigid structure. The entire surface of the said bottom 11 is covered by means of covering 44 constructed of fabric or some other suitable material which is hemmed over the edging wire 43, brought around the edging wire 41 and tacked to the facing 45 disposed at the forward portion of the base 28.

The rear seat section 12 is similarly constructed. This seat section comprises a base 52 having slats 53 which extend transversely of the said bottom and which are attached at their rearward ends to a longitudinal base member 54. The slats 53 are disposed below the slats 29. At the forward ends of the said slats are arranged posts 55 which have secured to the upper ends of the same a forward longitudinal base member 56. Other posts 57 are secured to the base member 54 and have attached to the upper ends of the same another longitudinal base member 58. The two base members 56 and 58 are angle-shaped and have upstanding legs 59 and horizontal legs 60 which rest on the posts 55 and 57. Tie bars 61 overlying the legs 60 stiffen the structure and prevent spreading of the legs. The base 52 is mounted on casters 47 similar to the casters 47.

Overlying the base 52 of seat bottom 12 are ribs 62 similar to the ribs 34 and which have attached to them arcuate leaf springs 63. The ribs 62 are also arranged in pairs indicated at 68 and each leaf spring is secured to the two ribs 62 of each pair. The rearward ends of the ribs 62 project rearwardly of the springs 63 and have secured to them clips 64 in which is mounted an edging wire 65.

It will be noted that the pairs of ribs 66 of the seat bottom 11 are spaced from one another to leave spaces 67 therebetween and similarly the pairs 68 of the leaves 62 are spaced from one another to leave spaces 69 therebetween. The pairs 68 of the ribs 62 are disposed in the spaces 67 while the pair 66 of the ribs 34 are disposed in the spaces 69. In this manner the two seat bottoms interfit, the pairs of ribs of each of said bottoms alternating with those of the other. The slats 29 and 53 being disposed below the pairs of ribs 66 and 68 and the parts 55 being disposed in the spaces 67 and 69, it will be readily comprehended that the posts 55 are movable in these spaces thus permitting the moving of two seat bottoms relative to one another from the position shown in Fig. 2 to that shown in Fig. 3.

For use in conjunction with the sofa a seat cushion 70 and a back rest cushion 71 are employed. These cushions being of conventional

construction have not been shown in detail. Both of the said cushions are of the same length, while the cushion 71 is slightly thicker than the cushion 70 to compensate for the slight difference in height between the two seat bottoms 11 and 12. The cushion 70 is, however, of a width substantially equal to the width of the seat bottom 11 while the cushion 71 is of a width equal to the difference between the widths of the two seat bottoms when in extended and collapsed position. This cushion is connected to the cushion 70 by means of a fabric flap 12 which is stitched to the upper rear edge 73 of the cushion 70 and to the lower forward edge 74 of the cushion 71.

The use of the invention is as follows: When the sofa bed is to be used as a sofa the forward seat bottom 11 is pushed rearward and the same rolls on the casters 47 to move the same inwardly into the space of the frame 10 of the sofa between the frame sections 13 and 14. The longitudinal base member 32 strikes the posts 55 of the seat bottom 12 and causes corresponding movement of the said seat bottom until the base 52 engages the rear longitudinal frame member 78 of said frame. Cushion 70 is then placed upon the combined seat bottoms and occupies the position illustrated in Fig. 3. The cushion 71 is moved forwardly and set on edge on cushion 70 with the flap 72 overlying the upper surface of the cushion 70 at the rearward portion thereof as shown. The said cushion is then brought into engagement with the back rest 23 of the frame 10 which serves to support the cushion in upright position resisting the pressure applied to the cushion by the user. The sides of the cushion 71 indicated at 75 are slightly beveled to make the cushion rest properly upon the cushion 70 and to cause the same to incline against the back rest 23. When desired for use as a bed, the seat bottom 11 is pulled outwardly rolling it on casters 47. As soon as the base member 33 engages the posts 55, the seat bottom 12 is drawn along with it and rolled on casters 141 and the parts moved outwardly until the same are relatively clear of the back rest 23. The cushion 71 is then laid upon the extended part of the seat bottom 12 which brings the flap in the position illustrated in Fig. 2. The said cushions are thus held in juxtaposition and now serve as a mattress.

The advantages of the invention are apparent. The sofa bed serves either as a sofa or as a full sized bed. With the invention extremely comfortable springs are provided which give equally as great comfort when the invention is used as a sofa as when the same is used as a bed. The operation of converting the sofa bed from bed to sofa and vice versa is extremely simple and is accomplished in a relatively small amount of time. No additional cushions or mattresses are needed, the sofa cushions forming the mattress. By means of the particular spring construction employed the ribs of the seat bottoms interfit and practically occupy no additional space when the seat bottoms are brought into register. By means of the flap connecting the cushions together the cushions are held in proper position whether the invention is used as a sofa or a bed. With the construction shown the seat cushion becomes of proper width for comfortable seating. When the parts are extended the cushions form a full sized mattress. By disposing the back rest cushion forwardly from the rear edge of the seat cushion a com-

partment is provided rearwardly of the back rest cushion and in which bedding and other materials may be stored.

Changes in the specific form of the invention, as herein described, may be made within the scope of what is claimed without departing from the spirit of the invention.

Having described the invention, what is claimed as new and desired to be protected by Letters Patent is:

- 10 1. In a sofa bed a front seat bottom comprising a base, a number of spaced ribs carried by said base, arcuate leaf springs extending between said ribs and base, a rear seat bottom comprising a base disposed below said first base, spaced ribs carried by said second base and disposed between certain of the first ribs, all of said ribs lying in a substantially horizontal plane, arcuate springs extending between said second ribs and said second base, and supporting means for guiding said seat bottoms for relative movement in the direction of the length of the ribs thereof.
- 15 2. In a sofa bed a front seat bottom comprising a base consisting of a number of spaced transverse slats, longitudinal base members arranged at the ends of the slats and secured thereto, a number of spaced transverse ribs overlying said base, springs extending between said ribs and longitudinal base members, a rear seat bottom comprising a base consisting of a number of spaced transverse slats disposed below said first slats, posts secured to certain of said slats at the ends thereof and projecting above said first slats, longitudinal base members mounted on said posts, a number of spaced transverse ribs overlying said second base, springs extending between said second ribs and said second longitudinal base members, said second ribs being disposed between said first ribs and said ribs all lying in a substantially horizontal plane, the rearmost of said first longitudinal base members being confined in movement to the space defined by said second ribs and slats and said second posts and springs, and supporting means for guiding said seat bottoms for relative movement in the direction of the length of the ribs thereof.
- 25 3. In a sofa bed a front seat bottom comprising a base consisting of a number of spaced transverse slats, longitudinal base members arranged at the ends of the slats and secured thereto, a number of spaced transverse ribs overlying said base, U-shaped leaf springs extending between the ends of said ribs and longitudinal base members, a rear seat bottom comprising a base consisting of a number of spaced transverse slats disposed below said first slats, posts secured to certain of said slats at the ends thereof and projecting above said first slats, longitudinal base members mounted on said posts, a number of spaced transverse ribs overlying said second base, C-shaped leaf springs extending between said second ribs and said second longitudinal base members, said second ribs being disposed between said first ribs and said ribs all lying in a substantially horizontal plane, the rearmost of said first longitudinal base members being confined in movement to the space defined by said second ribs and said second slats and said second posts and springs, and supporting means for guiding said seat bottoms for relative movement in the direction of the length of the ribs thereof.
- 30 4. In a sofa bed a front seat bottom comprising a base consisting of a number of spaced transverse slats, longitudinal base members arranged at the ends of the slats and secured thereto, a number of spaced transverse ribs overlying said base, U-shaped leaf springs extending between the ends of said ribs and longitudinal base members, a rear seat bottom comprising a base consisting of a number of spaced transverse slats disposed below said first slats, posts secured to certain of said slats at the ends thereof and projecting above said first slats, longitudinal base members mounted on said posts, a number of spaced transverse ribs overlying said second base, C-shaped leaf springs extending between said second ribs and said second longitudinal base members, said second ribs being disposed between said first ribs and said ribs all lying in a substantially horizontal plane, the rearmost of said first longitudinal base members being confined in movement to the space defined by said second ribs and said second slats and said second posts and springs, and supporting means for guiding said seat bottoms for relative movement in the direction of the length of the ribs thereof.
- 35 5. In a sofa bed a front seat bottom comprising a base consisting of a number of spaced transverse slats, longitudinal base members arranged at the ends of the slats and secured thereto, a number of spaced transverse ribs overlying said base, U-shaped leaf springs extending between the ends of said ribs and longitudinal base members, a rear seat bottom comprising a base consisting of a number of spaced transverse slats disposed below said first slats, posts secured to certain of said slats at the ends thereof and projecting above said first slats, longitudinal base members mounted on said posts, a number of spaced transverse ribs overlying said second base, C-shaped leaf springs extending between said second ribs and said second longitudinal base members, said second ribs being disposed between said first ribs and said ribs all lying in a substantially horizontal plane, the rearmost of said first longitudinal base members being confined in movement to the space defined by said second ribs and said second slats and said second posts and springs, and supporting means for guiding said seat bottoms for relative movement in the direction of the length of the ribs thereof.
- 40 6. In a sofa bed a front seat bottom comprising a base consisting of a number of spaced transverse slats, longitudinal base members arranged at the ends of the slats and secured thereto, a number of spaced transverse ribs overlying said base, U-shaped leaf springs extending between the ends of said ribs and longitudinal base members, a rear seat bottom comprising a base consisting of a number of spaced transverse slats disposed below said first slats, posts secured to certain of said slats at the ends thereof and projecting above said first slats, longitudinal base members mounted on said posts, a number of spaced transverse ribs overlying said second base, C-shaped leaf springs extending between said second ribs and said second longitudinal base members, said second ribs being disposed between said first ribs and said ribs all lying in a substantially horizontal plane, the rearmost of said first longitudinal base members being confined in movement to the space defined by said second ribs and said second slats and said second posts and springs, and supporting means for guiding said seat bottoms for relative movement in the direction of the length of the ribs thereof.
- 45 7. In a sofa bed a front seat bottom comprising a base consisting of a number of spaced transverse slats, longitudinal base members arranged at the ends of the slats and secured thereto, a number of spaced transverse ribs overlying said base, U-shaped leaf springs extending between the ends of said ribs and longitudinal base members, a rear seat bottom comprising a base consisting of a number of spaced transverse slats disposed below said first slats, posts secured to certain of said slats at the ends thereof and projecting above said first slats, longitudinal base members mounted on said posts, a number of spaced transverse ribs overlying said second base, C-shaped leaf springs extending between said second ribs and said second longitudinal base members, said second ribs being disposed between said first ribs and said ribs all lying in a substantially horizontal plane, the rearmost of said first longitudinal base members being confined in movement to the space defined by said second ribs and said second slats and said second posts and springs, and supporting means for guiding said seat bottoms for relative movement in the direction of the length of the ribs thereof.
- 50 8. In a sofa bed a front seat bottom comprising a base consisting of a number of spaced transverse slats, longitudinal base members arranged at the ends of the slats and secured thereto, a number of spaced transverse ribs overlying said base, U-shaped leaf springs extending between the ends of said ribs and longitudinal base members, a rear seat bottom comprising a base consisting of a number of spaced transverse slats disposed below said first slats, posts secured to certain of said slats at the ends thereof and projecting above said first slats, longitudinal base members mounted on said posts, a number of spaced transverse ribs overlying said second base, C-shaped leaf springs extending between said second ribs and said second longitudinal base members, said second ribs being disposed between said first ribs and said ribs all lying in a substantially horizontal plane, the rearmost of said first longitudinal base members being confined in movement to the space defined by said second ribs and said second slats and said second posts and springs, and supporting means for guiding said seat bottoms for relative movement in the direction of the length of the ribs thereof.
- 55 9. In a sofa bed a front seat bottom comprising a base consisting of a number of spaced transverse slats, longitudinal base members arranged at the ends of the slats and secured thereto, a number of spaced transverse ribs overlying said base, U-shaped leaf springs extending between the ends of said ribs and longitudinal base members, a rear seat bottom comprising a base consisting of a number of spaced transverse slats disposed below said first slats, posts secured to certain of said slats at the ends thereof and projecting above said first slats, longitudinal base members mounted on said posts, a number of spaced transverse ribs overlying said second base, C-shaped leaf springs extending between said second ribs and said second longitudinal base members, said second ribs being disposed between said first ribs and said ribs all lying in a substantially horizontal plane, the rearmost of said first longitudinal base members being confined in movement to the space defined by said second ribs and said second slats and said second posts and springs, and supporting means for guiding said seat bottoms for relative movement in the direction of the length of the ribs thereof.
- 60 10. In a sofa bed a front seat bottom comprising a base consisting of a number of spaced transverse slats, longitudinal base members arranged at the ends of the slats and secured thereto, a number of spaced transverse ribs overlying said base, U-shaped leaf springs extending between the ends of said ribs and longitudinal base members, a rear seat bottom comprising a base consisting of a number of spaced transverse slats disposed below said first slats, posts secured to certain of said slats at the ends thereof and projecting above said first slats, longitudinal base members mounted on said posts, a number of spaced transverse ribs overlying said second base, C-shaped leaf springs extending between said second ribs and said second longitudinal base members, said second ribs being disposed between said first ribs and said ribs all lying in a substantially horizontal plane, the rearmost of said first longitudinal base members being confined in movement to the space defined by said second ribs and said second slats and said second posts and springs, and supporting means for guiding said seat bottoms for relative movement in the direction of the length of the ribs thereof.
- 65 11. In a sofa bed a front seat bottom comprising a base consisting of a number of spaced transverse slats, longitudinal base members arranged at the ends of the slats and secured thereto, a number of spaced transverse ribs overlying said base, U-shaped leaf springs extending between the ends of said ribs and longitudinal base members, a rear seat bottom comprising a base consisting of a number of spaced transverse slats disposed below said first slats, posts secured to certain of said slats at the ends thereof and projecting above said first slats, longitudinal base members mounted on said posts, a number of spaced transverse ribs overlying said second base, C-shaped leaf springs extending between said second ribs and said second longitudinal base members, said second ribs being disposed between said first ribs and said ribs all lying in a substantially horizontal plane, the rearmost of said first longitudinal base members being confined in movement to the space defined by said second ribs and said second slats and said second posts and springs, and supporting means for guiding said seat bottoms for relative movement in the direction of the length of the ribs thereof.
- 70 12. In a sofa bed a front seat bottom comprising a base consisting of a number of spaced transverse slats, longitudinal base members arranged at the ends of the slats and secured thereto, a number of spaced transverse ribs overlying said base, U-shaped leaf springs extending between the ends of said ribs and longitudinal base members, a rear seat bottom comprising a base consisting of a number of spaced transverse slats disposed below said first slats, posts secured to certain of said slats at the ends thereof and projecting above said first slats, longitudinal base members mounted on said posts, a number of spaced transverse ribs overlying said second base, C-shaped leaf springs extending between said second ribs and said second longitudinal base members, said second ribs being disposed between said first ribs and said ribs all lying in a substantially horizontal plane, the rearmost of said first longitudinal base members being confined in movement to the space defined by said second ribs and said second slats and said second posts and springs, and supporting means for guiding said seat bottoms for relative movement in the direction of the length of the ribs thereof.
- 75 13. In a sofa bed a front seat bottom comprising a base consisting of a number of spaced transverse slats, longitudinal base members arranged at the ends of the slats and secured thereto, a number of spaced transverse ribs overlying said base, U-shaped leaf springs extending between the ends of said ribs and longitudinal base members, a rear seat bottom comprising a base consisting of a number of spaced transverse slats disposed below said first slats, posts secured to certain of said slats at the ends thereof and projecting above said first slats, longitudinal base members mounted on said posts, a number of spaced transverse ribs overlying said second base, C-shaped leaf springs extending between said second ribs and said second longitudinal base members, said second ribs being disposed between said first ribs and said ribs all lying in a substantially horizontal plane, the rearmost of said first longitudinal base members being confined in movement to the space defined by said second ribs and said second slats and said second posts and springs, and supporting means for guiding said seat bottoms for relative movement in the direction of the length of the ribs thereof.

ing a base consisting of a number of spaced transverse slats, longitudinal base members arranged at the ends of the slats and secured thereto, a number of spaced transverse ribs overlying said base, springs extending between said ribs and longitudinal base members, a rear seat bottom comprising a base consisting of a number of spaced transverse slats disposed below said first slats, posts secured to certain of said slats at the ends thereof and projecting above said first slats, longitudinal base members mounted on said posts, a number of spaced transverse ribs overlying said second base, springs extending between said second ribs and said second longitudinal base members, said second ribs being disposed between said first ribs and said ribs all lying in a substantially horizontal plane, the rearmost of said first longitudinal base members being confined in movement to the space defined by said second ribs and said second slats and said second posts and springs, and casters secured to said slats and guiding said seat bottoms for relative sliding movement in the direction of the length of the ribs thereof.

5. In a sofa bed, a front seat bottom and a rear seat bottom, said seat bottoms having transversely extending interfitting elongated parts formed with upper surfaces lying in a substantially horizontal plane and supporting means for guiding said seat bottoms for relative movement in the direction of the length of said parts, a seat cushion overlying said front seat bottom, a back rest cushion resting throughout its lower end upon the rearward part of said seat cushion inwardly of the rear edge thereof to reduce the width of the exposed portion of said seat cushion and a flap hinged to said cushions and holding the same in position to form a sofa or a mattress.

6. In a sofa bed, a front seat bottom and a rear seat bottom, said seat bottoms having transversely extending interfitting elongated parts formed with upper surfaces lying in a substantially horizontal plane and supporting means for guiding said seat bottoms for relative movement in the direction of the length of said parts, a seat cushion overlying said front seat bottom, a back rest cushion resting on edge

upon the rearward part of said seat cushion and a flap hinged to said seat cushion at the upper rear edge thereof and to said back rest cushion when in a horizontal position to the lower forward edge thereof, said flap being of a length equal to the thickness of said cushions.

7. In a sofa bed, a seat bottom, a seat cushion overlying said seat bottom, a back rest cushion resting on edge upon the rearward part of 10 said seat cushion, a flap hinged to said seat cushion at the upper rear edge thereof and to said back rest cushion when in erected position to the lower rear edge thereof and free from said cushions elsewhere, said flap being of a 15 length substantially equal to the thickness of said back rest cushion, said back rest cushion being adapted to lie in continuation of said cushion with the flap disposed between the ends of the cushions, said flap holding the upper surfaces of said cushions substantially in a common plane.

8. In a sofa bed a front seat bottom comprising a base, a number of spaced ribs carried by said base, arcuate leaf springs extending between 25 said ribs and base, a rear seat bottom comprising a base having parts disposed adjacent said first base, spaced ribs carried by said second base and disposed between certain of the first ribs, all of said ribs lying in a substantially horizontal plane, arcuate springs extending between 30 said second ribs and said second base, and supporting means for guiding said seat bottoms for relative movement in the direction of the length of the ribs thereof.
